UNITED STATES PATENT OFFICE.

TIMOTHY H. GRAVES, OF ALEXANDRIA, OHIO.

IMPROVEMENT IN SHIFTING-RAILS FOR VEHICLES.

Specification forming part of Letters Patent No. **222,487**, dated December 9, 1879; application filed May 26, 1879,

To all whom it may concern:

Be it known that I, TIMOTHY H. GRAVES, of Alexandria, in the county of Licking, and in the State of Ohio, have invented certain new and useful Improvements in Shifting-Rails for Vehicles; and I do hereby declare that the following is a full, clear, and exact description thereof, reference being had to the accompanying drawings, and to the letters of reference marked thereon, making a part of this specification.

The nature of my invention consists in the construction and arrangement of a rail for vehicle-seats, as will be hereinafter more fully set forth.

In order to enable others skilled in the art to which my invention appertains to make and use the same, I will now proceed to describe its construction and operation, referring to the annexed drawings, in which—

Figure 1 is a perspective view of a part of a vehicle-seat with my improved rail applied thereto. Fig. 2 is a detail section of a part thereof.

A represents a part of a vehicle-seat, to the sides and back of which are fastened the metal straps B B, having their ends projecting beyond the top edges thereof and perforated for the attachment of the rail.

D represents the main side rail, the front end of which is bent upward and outward and terminates in an outwardly-projecting bolt, a, as shown. The rear end of the side rail, D, is screwed into a corner-iron, which is formed with three straight arms, D', D², and D³. The arm D' extends forward, and the arm D² extends outward at right angles thereto. The arm D³ extends inward parallel to but in rear of the arm D².

The rear end of the side rail, D, is screwed into the end of the arm D'. Through the arm D² is passed a bolt, b, the head of which is countersunk in the inner side of the arm D'. This bolt passes longitudinally through the arm D², and a nut, d, is screwed on the end of the bolt against the end of the arm. The

bolt b and the bolt a are intended to form the supports for the bows of the buggy-top. In the end of the arm D³ is screwed the end of a rail, F, which extends inward, and is then curved upward and attached to the back G. To this back is also attached a rail, H, which curves downward and forward over the main side rail, D, the forward end of said rail H being turned downward and passed through a square box, I, on the rail D. This box I is welded on the rail D, and the hole for the end of the rail H is made through said box and through the rail D. The lower end of the rail H forms a bolt, e, on which is screwed a thumb-nut, J, for holding the parts together.

A small brace or rail, L, is welded to the rail H at a suitable point at or near its highest part, and its lower end is passed through a square box, I', the same as described for the box I, and its lower end forms a bolt, e', on which a thumb-nut, J', is screwed.

On the horizontal part of the back rail, F, is welded another square box, I², having a screw or bolt, e², passed vertically through it and through the rail, and on the end is placed a thumb-nut, J². The three bolts e e' e² are to be passed through the ends of the metal straps B, and nuts screwed on the ends to secure the rails in place to the seat.

Having thus fully described my invention, what I claim as new, and desire to secure by Letters Patent, is—

The combination of the side rail, D, with boxes I I', corner-iron D' D² D³, having the outward-projecting arm hollow, the rail F, with box I², rails H L, and bolts b and e², all constructed substantially as and for the purposes herein set forth.

In testimony that I claim the foregoing I have hereunto set my hand this 20th day of May, 1879.

TIMOTHY H. GRAVES.
